US00D934177S

(12) **United States Design Patent** (10) **Patent No.:** **US D934,177 S**
(45) **Date of Patent:** **** Oct. 26, 2021**

(54) **PLUG ADAPTER**

(71) Applicant: **Amazon Technologies, Inc.**, Seattle, WA (US)

(72) Inventors: **Wilfrido Loor Canizares**, San Francisco, CA (US); **Christopher Green**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/762,689**

(22) Filed: **Dec. 17, 2020**

Related U.S. Application Data

(62) Division of application No. 29/722,916, filed on Mar. 2, 2020, now Pat. No. Des. 911,969, which is a division of application No. 29/600,473, filed on Apr. 12, 2017, now Pat. No. Des. 874,403.

CLAIM

The ornamental design for a plug adapter, as shown and described.

DESCRIPTION

FIG. 1 is a top, back perspective view of a plug adapter; FIG. 2 is a top, front perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines shown in the drawings depict portions of the plug adapter that form no part of the claimed design.

1 Claim, 8 Drawing Sheets
